Primary Examiner — Susan Moon Lee

CLAIM

The ornamental design for a head portion of an oral care implement, as shown and described.

DESCRIPTION

FIG. 1 is a right front perspective view of a head portion of an oral care implement according to the new design;

FIG. 2 is a left front perspective view thereof;

FIG. 3 is a right rear perspective view thereof;

FIG. 4 is a left rear perspective view thereof;

FIG. 5 is a front view thereof;

FIG. 6 is a rear view thereof;

FIG. 7 is a right side view thereof;

FIG. 8 is a left side view thereof;

FIG. 9 is a top view thereof; and,

FIG. 10 is a bottom view thereof.

The portions depicted in broken lines illustrate parts of the oral care implement that form no part of the claimed design.

1 Claim, 5 Drawing Sheets
